Des. 208,631
Patented Sept. 19, 1967

208,631

FISH LURE

Earl E. Miller, Cass County, Mich., assignor to James Heddon's Sons, Dowagiac, Mich., a corporation of Michigan

Filed Dec. 5, 1966, Ser. No. 4,922

Term of patent 14 years

(Cl. D22—28)

FIGURE 1 is a side elevational view of a fish lure embodying my new design;

FIGURE 2 is a top plan view thereof;

FIGURE 3 is a bottom plan view thereof;

FIGURE 4 is a front elevational view thereof; and

FIGURE 5 is a rear elevational view thereof.

The dominant features of my design reside in the portions shown in full lines.

I claim:

The ornamental design for a fish lure, as shown and described.
